UNITED STATES PATENT OFFICE.

WILLIAM SHERMAN BROWN, OF KNOXVILLE, TENNESSEE.

STEAM-ENGINE VALVE-GEAR.

1,086,018.

Specification of Letters Patent.

Patented Feb. 3, 1914.

Application filed May 12, 1913. Serial No. 767,052.

To all whom it may concern:

Be it known that I, WILLIAM SHERMAN BROWN, a citizen of the United States, residing at Knoxville, in the county of Knox 5 and State of Tennessee, have invented a new and useful Improvement in Steam-Engine Valve-Gears, of which the following is a specification, reference being had to the accompanying drawing.

10 My improvement relates particularly to mechanism for transmitting motion from the crank of a drive wheel of a steam locomotive to the distributing valve which admits steam to the cylinder.

15 The object of the improvement is to provide a construction which is simple, has the parts accessibly located, and avoids irregularity of valve action due to lost motion or "pounding" at the crank.

20 This improvement is a modification of the mechanism described by my United States Patent No. 1,033,532, granted July 23, 1912, for "steam-engine valve-gear".

In the accompanying drawings, Figure 1 25 is a side elevation, portions being broken away, showing my improvement applied to one side of a locomotive; Fig. 2 is a plan of a portion of the mechanism shown by Fig. 1; Fig. 3 is a section on the line, 3—3, of Fig. 2, looking toward the right; Fig. 4 is a section on the line, 4—4, of Fig. 2, looking in the direction of the arrow; Fig. 5 is a plan of a bridge on which a rocking member is supported; Fig. 6 is a side elevation of 30 said bridge; Fig. 7 is a section on the line, 7—7, of Fig. 1, looking toward the left; Fig. 8 is an elevation of a combined bearing and standard; Fig. 9 is a side elevation similar to Fig. 1, illustrating a modification; Fig. 40 10 is a section on the line, 10—10, of Fig. 9, looking toward the left; Figs. 11 and 12 illustrate another modification; Figs. 13 and 14 illustrate another modification.

Referring to said drawings, 1, is the 45 usual valve stem extending to the distributing valve (not shown). The usual horizontal parallel cross-head guide bars, 2, are supported at their rear ends by the guide yoke extension, 3. The usual connecting 50 rod or pitman, 4, is coupled to the usual main crank, 5, carried by a drive wheel, D. On the main crank, 5, is rigidly mounted an auxiliary crank, 6, standing 90 degrees forward of the main crank. To said auxiliary 55 crank is coupled one end of the auxiliary pitman rod, 7.

A bridge B, is located above the frame, A, and extends from the ordinary guide-yoke, 8, and guide-yoke extension, 3, to the cross beam or plate, 10, and is secured to 60 said guide-yoke and to said cross-beam by means of bolts, 9. Said bridge is in the form of a plate having its length horizontal and being turned to bring its long edges into an upright plane. At its rear end, the 65 bridge has a lateral extension, 11, resting against the cross-beam, 10, and receiving said bolts, 9. At its forward end the bridge has a transverse extension, 12, reaching to both sides of the body of the bridge and 70 resting against the guide yoke, 8, and the guide yoke extension, 3, and receiving said bolts, 9. The innermost of said bolts extends through the transverse extension, 12, and the guide yoke, 8, while the others of 75 said bolts extend through the transverse extension, 12, and through the guide yoke, 8, and the guide yoke extension, 3. On the outer portion of the transverse extension, 12, and integral therewith is an ear, 13, 80 which is directed rearward, and on the inner portion of said transverse extension is another ear, 14, also directed rearward and located horizontally opposite the ear, 13. Each of said ears has a bearing, 15, receiving the ends of a shaft, 16. On said shaft is a bell crank or rocking member, F, preferably rotatable on said shaft, the latter being held immovably in its bearings. Said bell crank has two approximately horizontal 85 arms, 17, and a depending arm, 18. The latter arm is coupled to the valve-stem, 1. By rocking the bell crank, the valve stem is reciprocated.

An approximately upright link, 19, has 90 its upper end coupled to the arms 17, of the bell crank, while its lower end is coupled to the forward end of the auxiliary pitman rod, 7, both ends of said link being forked 100 to receive said rod and said arms, as shown in the drawings. Said arms, 17, are also forked to receive the upper ends of the link, 19. Rearward of the said bell crank the bridge has a lateral extension, C. On this portion of the bridge is seated a bearing 105 box, E, secured to the bridge by bolts, 20. Said box receives a short rock-shaft, 21, which is horizontal and transverse to the frame. On the outer end of said shaft, 21, is a rocking-arm, 22, directed upward and 110 having at its upper end a horizontal wrist, 23. An approximately upright oscillatory

arc lever, 24, has a transverse bearing, 25, between its ends, and the wrist, 23, extends through said bearing for supporting said lever. The upper section of the bearing 5 box, E, has an upward extension forming a standard, 26, in the upper end of which is an upright slot, 27, extending through said standard from the outer to the inner side thereof. In said slot, is a slide-block, 28. 10 A bolt, 29, extends through the upper end of the arc lever, 24, and through said slide-block, it being loose for rotation in said lever or said block, whereby the upper end of said lever is held for up and down reciprocation and for oscillation of its lower portion on the axis of the bolt, 29. If the bolt, 29, and the slide-block, 28, were stationary during the oscillation of said arc lever, the path traversed by the bolt, 31, in 15 the lower end of the arc lever, would be concentric to the axis of the bolt, 29. But such path is modified by the bodily lowering of the arc lever during its movement away from the upright plane in which lies the axis 20 of the rock-shaft, 21, as will hereinafter appear. To the lower end of the arc lever is coupled the upper end of an approximately upright link, 30, by means of a bolt, 31, the upper end of said link being forked to receive the lower end of the arc lever. The 25 lower end of said link is coupled to the auxiliary pitman rod, 7, by means of a bolt, 32, in the upright plane in which the axis of the rock-shaft, 21, lies, the location for said bolt being taken when the auxiliary crank 30 is on either the upper or the lower quarter. As above stated, during each oscillation, the path of the bolt, 31, is modified by the bodily downward movement of the arc lever 35 as it moves toward each extreme of its oscillation. This modification involves an inversion of the curve so that said path becomes concentric to an axis below said path. The height of said axis may be varied by varying the relative proportions of the rocking arm, 45 22, the arc lever, 24, and the link, 30. For best results, said axis is to be made coincident with the lower axis of the link, 30, (which is the axis of the bolt, 32), when 30 the lower end of said link is at the middle of its path of oscillation, which middle is, as above stated, in the upright plane in which the axis of the rock shaft, 21, lies. The forward end of an auxiliary reach 40 55 rod, 33, is coupled to the arc lever, 24, by means of the bolt, 31, said rod lying beside the lower end of the arc lever within the fork of the link, 30. The rear end of said auxiliary reach rod is coupled to the upper 60 right arm, 34, which is rigid on the rock-shaft, 35, which shaft is supported in bearings, 36. On said rock-shaft is an arm, 37, to which is coupled a rod, 38, which is in turn coupled to the ordinary reversing lever, 65 70 working on a sector or quadrant, 40.

In operation, the arc lever is set to bring its lower end into any desired position in its curved path, this being done by means of the reversing lever; and while said arc lever is so set, the link, 30, oscillates on the lower end of said arc lever (on the axis of the bolt, 31,) during each reciprocation of the auxiliary pitman rod, the axis of the bolt, 32, moving in an arc in which lies the axis to which the path of the lower end of the arc lever, or of the bolt, 31, is concentric. And, as above indicated, the distance between the wrist of the auxiliary crank, 6, and the bolt, 32, is such as to bring the axis of said bolt into the axis of the arc path of the lower end of the arc lever when said crank is on the upper or the lower quarter, at which time the main crank is on either the front or the rear quarter. In Fig. 1, it is shown on the front quarter, the auxiliary crank being 80 on the top quarter. During each such reciprocation, said auxiliary pitman rod rocks bodily with the axis of the bolt, 32, as a fulcrum. This involves the rising and falling of the forward end of said auxiliary rod, and during such movement of said end of said rod, the link, 17, is forced up and down, and such movement of said link causes the rocking of the bell crank, F, and the reciprocation of the valve stem, 1.

The gear is reversed by throwing the reversing lever across the center in the usual manner, and the opening of the valve is varied by moving the lower end of the arc lever nearer to and farther from the plane in which the axis of the rock shaft, 21, lies, this being accomplished by the aid of suitable notches (not shown) on the reversing lever sector. When the lower end of the arc lever is on the middle of its path (or in said upright plane), the valve motion is reduced to the extent of the "lead."

In the form illustrated by Figs. 9 and 10, the rock-shaft, 35, bearings, 35, arm 34, and auxiliary reach rod, 33, are omitted, and a longer rock-shaft, 41, is substituted for the rock-shaft, 21, of Fig. 7, and the reach arm, 42, corresponding to the arm, 37, on the rock-shaft, 35, is placed on the shaft, 41, and its upper end coupled to the forward end of the reach rod, 38. The rocking arm, 22, is placed upon the outer end of the shaft, 41, the same as said arm is placed on the shaft, 21, in Fig. 7.

Figs. 11 and 12 illustrate a form which is in part an inversion of the forms already described. The rock-shaft, 21, is present as in Fig. 7, and on said shaft is the rocking arm, 22, of Fig. 7, but it is turned downward. A standard, 44, is fastened to the frame, A, below the shaft, 21, and the arm, 43, and has an upright slot, 45, in which is a slide-block, 46. An arc lever, 47, corresponds to the arc lever, 24, of the preceding forms but it is inverted. It has a bearing,

48, corresponding to the bearing, 25, of the lever 24. At its lower end a bolt, 49, extends through the lower end of said lever and through the slide-block, 46, said bolt being loose to permit the upper portion of said arc lever to oscillate with said bolt for an axis. The upper end of said arc lever is coupled to the upper end of the link, 30, by means of a bolt, 50, in an arc having a radius 5 equal to the length of the lever, 47. But while the upper end of the arc lever moves away from its middle position it is carried bodily upward by the rocking arm, 43, whereby there is formed an arc, the radius 10 of which is longer than the arc lever, 47, as long as the link, 30, if the parts are suitably proportioned. The forward end of the auxiliary reach rod, 33, (shown in Fig. 1) is coupled to the upper end of the arc lever, 47, 15 said reach rod being placed between the link, 30, and the lever, 47, and the bolt, 50, extending through said reach rod as well as through said lever and link.

In Figs. 13 and 14, the auxiliary reach rod 25 is omitted, the rock-shaft, 21, is extended to become the rock-shaft, 41, of Fig. 9, and on said shaft is an arm, 42, to the upper end of which is coupled directly to the reach rod, 38; as shown in Fig. 9.

The drawings have been copied, in part, 30 from larger working drawings used in applying my improvement to a railway freight locomotive having a piston stroke of 30 inches and having a maximum valve travel of $5\frac{1}{2}$ inches and a lead of three sixteenths of an inch. The radius of the auxiliary crank, 6, (measuring from the driver axis) is 8 and $\frac{1}{2}$ inches. The distance from the auxiliary crank along the auxiliary pitman rod, 7, to 35 the axis of the bolt, 32, is $7\frac{1}{4}$ and $3\frac{1}{2}$ inches. From the latter point on said pitman rod to 40 the link, 17, is $10\frac{1}{2}$ and $1\frac{1}{2}$ inches. The length of the link, 30, is $35\frac{1}{16}$ inches, and that, as already described, is also the radius of 45 the curved path of the bolt, 31, which carries the upper end of the link, 30; and the center of said curved path coincides with the axis of the bolt, 33, when the auxiliary crank is on the upper quarter or the lower quarter, at which time said bolt is one and five sixteenths inches below the level of the driver axis and the cylinder axis (the "working line" or "center line of motion"). The length of the link, 17, is 32 inches. The 50 height of the axis or fulcrum of the bell crank of rocking member, C, above the level of the center line of motion is $32\frac{1}{8}$ inches. The length of the arms, 15 and 16, of the bell crank is $12\frac{1}{4}$ and $\frac{1}{8}$ inches. The 55 rocking member, C, as used on said engine, is not a true bell crank, its angle being less than ninety degrees—72 degrees.

When the engine is in forward motion and the main crank is on the back center and the 60 auxiliary crank on the upper quarter, the 65

arm, 15, is 2 and $\frac{1}{2}$ degrees back of a vertical line cutting the fulcrum, and the arc, 15, is 15 and $\frac{1}{2}$ degrees below a horizontal line cutting the fulcrum. When the arc lever is set for full valve travel (5 and $\frac{1}{2}$ inches), the 70 forward travel of the arm, 16, from the position mentioned is 7 and $\frac{1}{2}$ degrees and the back travel of said arm from said position of 19 degrees, and the arm, 15, travel downward and upward correspondingly. Thus 75 the larger portion of the travel of the rocking member arms is within the 90 degree angle formed by said vertical and said horizontal lines. These relative proportions and 80 positions of the various parts of the mechanism produce the desired quick movement of the valve during the opening and closing and also produce equalized travel of the valve over the port during the forward motion and during the backward motion. 85

It is to be observed that my improvement eliminates from the valve mechanism the eccentric and also all parts having a high velocity. No part of the valve mechanism is connected to the connecting rod nor the cross-head. Movement is transmitted to the valve stem from the wrist of the auxiliary crank and said wrist travels in a relatively small circle. Thus the movement of the auxiliary rod and the links, 17, and 30, are 90 through relatively short ranges. Furthermore, it is to be noted that lost motion due to wear at the wrist of the auxiliary crank will chiefly modify the lengthwise movement of the auxiliary pitman, 7, while the movement transmitted through the link, 17, is approximately at right angles to said auxiliary pitman. Hence the modification of the longitudinal movement of said pitman is substantially not transmitted to said link. And 95 it will be seen that such modification of the rocking movement of the auxiliary pitman due to wear at the wrist of the auxiliary crank will affect the link, 17, in minimized form, because the portion of the auxiliary pitman between the axis, 32, and the link, 17, is much less than between said axis and the wrist of the auxiliary crank. In this connection it is to be remembered that wear by the auxiliary crank wrist in the auxiliary 100 pitman is chiefly in the direction of the length of said pitman. Such wear produces 105 what is termed lost motion or "pounding" 110 at the crank.

I claim as my invention:

1. In a steam engine valve gear, the combination of a rocking member, means for rocking said rocking member, an upright, reciprocatory arc lever coupled between its ends to the outer end of said rocking member, means for guiding one end of said arc lever for approximately upright reciprocation, an auxiliary crank, an auxiliary rod coupled to said crank, and two approximately upright links, each having its lower 115 120 125 130

- end coupled to the auxiliary rod and one having its upper end coupled to the oscillatory end of the arc lever and the other having its upper end in operative relation with the distributing valve stem, substantially as described.
2. In a steam engine valve gear, the combination of a rocking member, means for rocking said rocking member, an upright, reciprocatory arc lever coupled between its ends to the outer end of said rocking member, means forming an upright slideway connection for one end of said arc lever, an auxiliary crank, an auxiliary rod coupled to said crank, and two approximately upright links, each having its lower end coupled to the auxiliary rod and one having its upper end coupled to the oscillatory end of the arc lever and the other having its upper end in operative relation with the distributing valve stem, substantially as described.
3. In a steam engine valve gear, the combination of a rocking member, an upright, reciprocatory arc lever coupled between its ends to the outer end of said rocking member, means for guiding one end of said arc lever for approximately upright reciprocation, an auxiliary crank, an auxiliary rod coupled to said crank, and two approximately upright links, each having its lower end coupled to the auxiliary rod and the rear of said links having its upper end coupled to the oscillatory end of the arc lever and the other link having its upper end in operative relation with the distributing valve stem, substantially as described.
4. In a steam engine valve gear, the combination of a rocking member, means for rocking said rocking member, an upright, reciprocatory arc lever coupled between its ends to the outer end of said rocking member, means forming an upright slide way connection for one end of said arc lever, an auxiliary crank, an auxiliary rod coupled to said crank, and two approximately upright links, each having its lower end coupled to the auxiliary rod and the rear of said links having its upper end coupled to the oscillatory end of the arc lever and the other link having its upper end in operative relation with the distributing valve stem, substantially as described.
5. In a steam engine valve gear, the combination of a rocking member, means for rocking said rocking member, an upright, reciprocatory arc lever coupled between its ends to the outer end of said rocking member, a fixed standard in operative relation with one end of said arc lever for limiting said end to upright movement, an auxiliary crank, an auxiliary rod coupled to said crank, and two approximately upright links, each having its lower end coupled to the auxiliary rod and one having its upper end coupled to the oscillatory end of the arc lever and the other having its upper end in operative relation with the distributing valve stem, substantially as described.
6. In a steam engine valve gear, the combination of a rocking member, an upright, reciprocatory arc lever coupled between its ends to the outer end of said rocking member, a fixed standard in operative relation with one end of said arc lever for limiting said end to upright movement, an auxiliary crank, an auxiliary rod coupled to said crank, and two approximately upright links, each having its lower end coupled to the auxiliary rod and one having its upper end coupled to the oscillatory end of the arc lever and the other having its upper end in operative relation with the distributing valve stem, substantially as described.
7. In a steam engine valve gear, the combination of a rocking member, an upright reciprocatory arc lever coupled between its ends through the outer end of said rocking member, a fixed standard in operative relation with one end of said arc lever for limiting said end to upright movement, an auxiliary crank, an auxiliary rod coupled to said crank, and two approximately upright links, each having its lower end coupled to the auxiliary rod and the rear of said links having its upper end coupled to the oscillatory end of the arc lever and the other link having its upper end in operative relation with the distributing valve stem, substantially as described.
8. In a steam engine valve gear, the combination of a rocking member, means for rocking said rocking member, an upright, reciprocatory arc lever coupled between its ends to the outer end of said rocking member, a fixed standard in operative relation with one end of said arc lever for limiting said ends to upright movement, an auxiliary crank, an auxiliary rod coupled to said crank, and two approximately upright links, each having its lower end coupled to the auxiliary rod and the rear of said links having its upper end coupled to the oscillatory end of the arc lever and the other link having its upper end in operative relation with the distributing valve stem, substantially as described.
9. In a steam engine valve gear, the combination of a bearing box, a standard integral with said box, a rocking member in said box, means for rocking said rocking member, an upright, reciprocatory arc lever coupled between its ends to the outer end of said rocking member, means for connecting one end of said arc lever in operative relation with said standard for approximately upright reciprocation, an auxiliary crank, an auxiliary rod coupled to said crank, and two approximately upright links, each having its lower end coupled to the auxiliary rod and one having its upper end coupled to the oscillatory end of the arc lever and the other having its upper end in operative relation with the distributing valve stem, substantially as described.

coupled to the oscillatory end of the arc lever and the other having its upper end in operative relation with the distributing valve stem, substantially as described.

- 5 10. In a steam engine valve gear, the combination of a bearing box, a standard integral with said box, a rocking member in said box, means for rocking said rocking member, an upright, reciprocatory arc lever coupled between its ends to the outer end of said rocking member, means connecting one end of said arc lever in operative relation with said standard for approximately upright reciprocation, an auxiliary crank, an auxiliary rod coupled to said crank, and two approximately upright links, each having its lower end coupled to the auxiliary rod and the rear of said links having its upper end coupled to the oscillatory end of the arc lever and the other link having its upper end in operative relation with the distributing valve stem, substantially as described.
- 10 15 20 25 30 35 40

11. In a steam engine valve gear, the combination of a bearing box, a standard integral with said box, a rocking member in said box, means for rocking said rocking member, an upright, reciprocatory arc lever coupled between its ends to the outer end of said rocking member, means for connecting one end of said arc lever in operative relation with said standard for approximately upright reciprocation, an auxiliary crank, an auxiliary rod coupled to said crank, and two approximately upright links, each having its lower end coupled to the auxiliary rod and one having its upper end coupled to the oscillatory end of the arc lever and the other having its upper end in operative relation with the distributing valve stem, substantially as described.

- 45 50 55 60 65 70 75 80 85 90 95 100 105 110 115 120 125 130
12. In a steam engine valve gear, the combination of a bearing box, a standard integral with said box, a rocking member in said box, means for rocking said rocking member, an upright, reciprocatory arc lever coupled between its ends to the outer end of said rocking member, means for connecting one end of said arc lever in operative relation with said standard for approximately upright reciprocation, an auxiliary crank, an auxiliary rod coupled to said crank, and two approximately upright links, each having its lower end coupled to the auxiliary rod and the rear of said links having its upper end coupled to the oscillatory end of the arc lever and the other link having its upper end in operative relation with the distributing valve stem, substantially as described.

- 60 65 70 75 80 85 90 95 100 105 110 115 120 125 130
13. In a steam engine valve gear, the combination of a rocking member, means for rocking said rocking member, an upright, reciprocatory arc lever coupled between ends to the outer end of said rocking member, means for guiding one end of said arc lever for ap-

proximately upright reciprocation, an auxiliary crank, an auxiliary rod coupled to said crank, two approximately upright links, each having its lower end coupled to the auxiliary rod and one having its upper end coupled to the oscillatory end of the arc lever, and a bell crank coupled to the upper end of the other of said links and connected in operative relation with the distributing valve stem, substantially as described.

- 70 75 80 85 90 95 100 105 110 115 120 125 130
14. In a steam engine valve gear, the combination of a rocking member, means for rocking said rocking member, an upright, reciprocatory arc lever coupled between its ends to the outer end of said rocking member, means forming an upright slideway connection for one end of said arc lever, an auxiliary crank, an auxiliary rod coupled to said crank, two approximately upright links, each having its lower end coupled to the auxiliary rod and one having its upper end coupled to the oscillatory end of the arc lever, and a bell crank coupled to the upper end of the other of said links and connected in operative relation with the distributing valve stem, substantially as described.

15. In a steam engine valve gear, the combination of a rocking member, an upright, reciprocatory arc lever coupled between its ends to the outer end of said rocking member, means for guiding one end of said arc lever for approximately upright reciprocation, an auxiliary crank, an auxiliary rod coupled to said crank, two approximately upright links, each having its lower end coupled to the auxiliary rod and one having its upper end coupled to the oscillatory end of the arc lever, and a bell crank coupled to the upper end of the other of said links and connected in operative relation with the distributing valve stem, substantially as described.

- 110 115 120 125 130
16. In a steam engine valve gear, the combination of a rocking member, means for rocking said rocking member, an upright, reciprocatory arc lever coupled between its ends to the outer end of said rocking member, means forming an upright slideway connection for one end of said arc lever, an auxiliary crank, an auxiliary rod coupled to said crank, two approximately upright links, each having its lower end coupled to the auxiliary rod and one having its upper end coupled to the oscillatory end of the arc lever, and a bell crank coupled to the upper end of the other of said links and connected in operative relation with the distributing valve stem, substantially as described.

17. In a steam engine valve gear, the combination of a rocking member, means for rocking said rocking member, an upright, reciprocatory arc lever coupled between its ends to the outer end of said rocking member, a fixed standard in operative relation with one end of said arc lever for limiting

bell crank coupled to the upper end of the other of said links and connected in operative relation with the distributing valve stem, substantially as described.

- 5 25. In a steam engine valve gear, the combination of a rocking member, an auxiliary reach rod in operative relation with said rocking member, a reversing lever, a rock shaft in operative relation with said reversing lever and said reach rod, an upright, reciprocatory arc lever coupled between its ends to the outer end of said rocking member, means for guiding one end of said arc lever for approximately upright reciprocation, an auxiliary crank, an auxiliary rod coupled to said crank, and two approximately upright links, each having its lower end coupled to the auxiliary rod and one having its upper end coupled to the oscillatory end of the arc lever and the other having its upper end in operative relation with the distributing valve stem, substantially as described.
- 10 26. In a steam engine valve gear, the combination of a rocking member, an auxiliary reach rod in operative relation with said rocking member, a reversing lever, a rock shaft in operative relation with said reversing lever and said reach rod, an upright, reciprocatory arc lever coupled between its ends to the outer end of said rocking member, means forming an upright slide way connection for one end of said arc lever, an auxiliary crank, an auxiliary rod coupled to said crank, and two approximately upright links, each having its lower end coupled to the auxiliary rod and one having its upper end coupled to the oscillatory end of the arc lever and the other having its upper end in operative relation with the distributing valve stem, substantially as described.
- 15 27. In a steam engine valve gear, the combination of a rocking member, means for rocking said rocking member, an upright, reciprocatory arc lever coupled between its ends to the outer end of said rocking member, means for guiding one end of said arc lever for approximately upright reciprocation, an auxiliary crank, an auxiliary rod coupled to said crank, and an approximately upright link having its lower end coupled to said auxiliary rod between the ends of the latter and having its upper end coupled to the oscillatory end of the arc lever, and means connecting the outer end of said auxiliary rod into operative relation with the stem of the distributing valve, substantially as described.
- 20 28. In a steam engine valve gear, the combination of a rocking member extending upward from its bearing, means for rocking said rocking member, an upright, reciprocatory arc lever coupled between its ends to the upper end of said rocking member, means for guiding the upper end of said arc lever for approximately upright reciprocation, an auxiliary crank, an auxiliary rod coupled to said crank, and two approximately upright links, each having its lower end coupled to the auxiliary rod and one having its upper end coupled to the oscillatory end of the arc lever and the other having its upper end in operative relation with the distributing valve stem, substantially as described.

lever for approximately upright reciprocation, an auxiliary crank, an auxiliary rod coupled to said crank, and two approximately upright links, each having its lower end coupled to the auxiliary rod and one having its upper end coupled to the lower end of the arc lever and the other having its upper end in operative relation with the distributing valve stem, substantially as described. 73

29. In a steam engine valve gear, the combination of a rocking member extending upward from its bearing, means for rocking said rocking member, an upright, reciprocatory arc lever coupled between its ends to the upper end of said rocking member, means forming an upright slide way connection for the upper end of said arc lever, an auxiliary crank, an auxiliary rod coupled to said crank, and two approximately upright links, each having its lower end coupled to the auxiliary rod and one having its upper end coupled to the lower end of the arc lever and the other having its upper end in operative relation with the distributing valve stem, substantially as described. 75

30. In a steam engine valve gear, the combination of a rocking member extending upward from its bearing, an upright, reciprocatory arc lever coupled between its ends to the upper end of said rocking member, means for guiding the upper end of said arc lever for approximately upright reciprocation, an auxiliary crank, an auxiliary rod coupled to said crank, and two approximately upright links, each having its lower end coupled to the auxiliary rod and the rear of said links having its upper end coupled to the lower end of the arc lever and the other link having its upper end in operative relation with the distributing valve stem, substantially as described. 95

31. In a steam engine valve gear, the combination of a rocking member extending upward from its bearing, means for rocking said rocking member, an upright, reciprocatory arc lever coupled between its ends to the upper end of said rocking member, means forming an upright slide way connection for the upper end of said arc lever, an auxiliary crank, an auxiliary rod coupled to said crank, and two approximately upright links, each having its lower end coupled to the auxiliary rod and the rear of said links having its upper end coupled to the lower end of the arc lever and the other link having its upper end in operative relation with the distributing valve stem, substantially as described. 100

32. In a steam engine valve gear, the combination of a rocking member extending upward from its bearing, means for rocking said rocking member, an upright, reciprocatory arc lever coupled between its ends to the upper end of said rocking member, 125

- 60 65. means for guiding the upper end of said arc

fixed standard in operative relation with the upper end of said arc lever for limiting said end to upright movement, an auxiliary crank, an auxiliary rod coupled to said crank, and two approximately upright links, each having its lower end coupled to the auxiliary rod and one having its upper end coupled to the lower end of the arc lever and the other having its upper end in operative relation with the distributing valve stem, substantially as described.

33. In a steam engine valve gear, the combination of a rocking member extending upward from its bearing, means for rocking said rocking member, an upright, reciprocatory arc lever coupled between its ends to the upper end of said rocking member, a fixed standard in operative relation with the upper end of said arc lever for limiting said end to upright movement, an auxiliary crank, an auxiliary rod coupled to said crank, and two approximately upright links, each having its lower end coupled to the auxiliary rod and one having its upper end coupled to the lower end of the arc lever and the other having its upper end in operative relation with the distributing valve stem, substantially as described.

34. In a steam engine valve gear, the combination of a rocking member extending upward from its bearing, an upright reciprocatory arc lever coupled between its ends to the upper end of said rocking member, a fixed standard in operative relation with the upper end of said arc lever for limiting said end to upright movement, an auxiliary crank, an auxiliary rod coupled to said crank, and two approximately upright links, each having its lower end coupled to the auxiliary rod and the rear of said links having its upper end coupled to the lower end of the arc lever and the other link having its upper end in operative relation with the distributing valve stem, substantially as described.

35. In a steam engine valve gear, the combination of a rocking member extending upward from its bearing means for rocking said rocking member, an upright, reciprocatory arc lever coupled between its ends to the upper end of said rocking member, a fixed standard in operative relation with the upper end of said arc lever for limiting said ends to upright movement, an auxiliary crank, an auxiliary rod coupled to said crank, and two approximately upright links, each having its lower end coupled to the auxiliary rod and the rear of said links having its upper end coupled to the lower end of the arc lever and the other link having its upper end in operative relation with the distributing valve stem, substantially as described.

36. In a steam engine valve gear, the combination of a bearing box, a standard in-

tegral with said box, a rocking member resting in and rising from said box, means for rocking said rocking member, an upright, reciprocatory arc lever coupled between its ends to the upper end of said rocking member, means for connecting the upper end of said arc lever in operative relation with said standard for approximately upright reciprocation, an auxiliary crank, an auxiliary rod coupled to said crank, and two approximately upright links, each having its lower end coupled to the auxiliary rod and one having its upper end coupled to the lower end of the arc lever and the other having its upper end in operative relation with the distributing valve stem, substantially as described.

37. In a steam engine valve gear, the combination of a rocking member extending upward from its bearing, an upright, reciprocatory arc lever coupled between its ends to the upper end of said rocking member, means for guiding the upper end of said arc lever for approximately upright reciprocation, an auxiliary crank, an auxiliary rod coupled to said crank, two approximately upright links, each having its lower end coupled to the auxiliary rod and one having its upper end coupled to the lower end of the arc lever, and a bell crank coupled to the upper end of the other of said links and connected in operative relation with the distributing valve stem, substantially as described.

38. In a steam engine valve gear, the combination of a rocking member extending upward from its bearing, means for rocking said rocking member, an upright, reciprocatory arc lever coupled between its ends to the upper end of said rocking member, means forming an upright slide way connection for the upper end of said arc lever, an auxiliary crank, an auxiliary rod coupled to said crank, two approximately upright links, each having its lower end coupled to the auxiliary rod and one having its upper end coupled to the lower end of the arc lever and a bell crank coupled to the upper end of the other of said links and connected in operative relation with the distributing valve stem, substantially as described.

39. In a steam engine valve gear, the combination of a rocking member extending upward from its bearing, means for rocking said rocking member, an upright, reciprocatory arc lever coupled between its ends to the upper end of said rocking member, a fixed standard in operative relation with the upper end of said arc lever for limiting said end to upright movement, an auxiliary crank, an auxiliary rod coupled to said crank, two approximately upright links, each having its lower end coupled to the auxiliary rod and one having its upper end coupled to the lower end of the arc lever and

a bell crank coupled to the upper end of the other of said links and connected in operative relation with the distributing valve stem, substantially as described.

5. 40. In a steam engine valve gear, the combination of a rocking member extending upward from its bearing, means for rocking said rocking member, an upright, reciprocatory arc lever coupled between its ends to the upper end of said rocking member, a fixed standard in operative relation with the upper end of said arc lever for limiting said end to upright movement, an auxiliary crank, an auxiliary rod coupled to said crank, two approximately upright links, each having its lower end coupled to the auxiliary rod and one having its upper end coupled to the lower end of the arc lever, and a bell crank coupled to the upper end of the other of said links and connected in operative relation with the distributing valve stem, substantially as described.

41. In a steam engine valve gear, the combination of a rocking member extending upward from its bearing, an upright, reciprocatory arc lever coupled between its ends to the upper end of said rocking member, a fixed standard in operative relation with the upper end of said arc lever for limiting said end to upright movement, an auxiliary crank, an auxiliary rod coupled to said crank, two approximately upright links, each having its lower end coupled to the auxiliary rod and one having its upper end coupled to the lower end of the arc lever, and a bell crank coupled to the upper end of the other of said links and connected in operative relation with the distributing valve stem, substantially as described.

40. 42. In a steam engine valve gear, the combination of a rocking member extending upward from its bearing, means for rocking said rocking member, an upright, reciprocatory arc lever coupled between its ends to the upper end of said rocking member, a fixed standard in operative relation with the upper end of said arc lever for limiting said end to upright movement, an auxiliary crank, an auxiliary rod coupled to said crank, two approximately upright links, each having its lower end coupled to the auxiliary rod and one having its upper end coupled to the lower end of the arc lever, and a bell crank coupled to the upper end of the other of said links and connected in operative relation with the distributing valve stem, substantially as described.

43. In a steam engine valve gear, the combination of a rocking member, a reversing lever, a reversing shaft in operative relation with said lever and said rocking member, an upright, reciprocatory arc lever coupled between its ends to the outer end of said rocking member, means for guiding one end of said arc lever for approximately upright

reciprocation, an auxiliary crank, an auxiliary rod coupled to said crank, and two approximately upright links, each having its lower end coupled to the auxiliary rod and one having its upper end coupled to the oscillatory end of the arc lever and the other having its upper end in operative relation with the distributing valve stem, substantially as described.

70. 44. In a steam engine valve gear, the combination of a rocking member, a reversing lever, a reversing shaft in operative relation with said lever and said rocking member, an upright, reciprocatory arc lever coupled between its ends to the outer end of said rocking member, means forming an upright slideway connection for one end of said arc lever, an auxiliary crank, an auxiliary rod coupled to said crank, and two approximately upright links, each having its lower end coupled to the auxiliary rod and one having its upper end coupled to the oscillatory end of the arc lever and the other having its upper end in operative relation with the distributing valve stem, substantially as described.

75. 45. In a steam engine valve gear, the combination of a rocking member, a reversing lever, a reversing shaft in operative relation with said lever and said rocking member, an upright, reciprocatory arc lever coupled between its ends to the outer end of said rocking member, means for guiding one end of said arc lever for approximately upright reciprocation, an auxiliary crank, an auxiliary rod coupled to said crank, and two approximately upright links, each having its lower end coupled to the auxiliary rod and the rear of said links having its upper end coupled to the oscillatory end of the arc lever and the other link having its upper end in operative relation with the distributing valve stem, substantially as described.

90. 46. In a steam engine valve gear, the combination of a rocking member, a reversing lever, a reversing shaft in operative relation with said lever and said rocking member, an upright, reciprocatory arc lever coupled between its ends to the outer end of said rocking member, means forming an upright slideway connection for one end of said arc lever, an auxiliary crank, an auxiliary rod coupled to said crank, and two approximately upright links, each having its lower end coupled to the auxiliary rod and the rear of said links having its upper end coupled to the oscillatory end of the arc lever and the other link having its upper end in operative relation with the distributing valve stem, substantially as described.

95. 47. In a steam engine valve gear, the combination of a rocking member extending upward from its bearing, a reversing lever, a reversing shaft in operative relation with said reversing lever and with said rocking

member, an upright, reciprocatory arc lever coupled between its ends to the upper end of said rocking member, means for guiding the upper end of said arc lever for approximately upright reciprocation, an auxiliary crank, an auxiliary rod coupled to said crank, and two approximately upright links, each having its lower end coupled to the auxiliary rod and one having its upper end coupled to the lower end of the arc lever and the other having its upper end in operative relation with the distributing valve stem, substantially as described.

48. In a steam engine valve gear, the combination of a rocking member extending upward from its bearing, a reversing lever, a reversing shaft in operative relation with said reversing lever and with said rocking member, an upright, reciprocatory arc lever coupled between its ends to the upper end of said rocking member, means forming an upright slide way connection for the upper end of said arc lever, an auxiliary crank, an auxiliary rod coupled to said crank, and two approximately upright links, each having its lower end coupled to the auxiliary rod and one having its upper end coupled to the lower end of the arc lever and the other having its upper end in operative relation with the distributing valve stem, substantially as described.

49. In a steam engine valve gear, the combination of a rocking member extending upward from its bearing, a reversing lever, a reversing shaft in operative relation with said lever and with said rocking member, an upright, reciprocatory arc lever coupled between its ends of the upper end of said rocking member, means for guiding the upper end of said arc lever for approximately upright reciprocation, an auxiliary crank, an auxiliary rod coupled to said crank, and two approximately upright links, each having its lower end coupled to the auxiliary rod and the rear of said links having its upper end coupled to the lower end of the arc lever and the other link having its upper end in operative relation with the distributing valve stem, substantially as described.

50. In a steam engine valve gear, the combination of a rocking member extending upward from its bearing, a reversing lever, a reversing shaft in operative relation with said reversing lever and with said rocking member, an upright, reciprocatory arc lever coupled between its ends to the upper end of said rocking member, means forming an upright slide way connection for the upper end of said arc lever, an auxiliary crank, an auxiliary rod coupled to said crank, and two approximately upright links, each having its lower end coupled to the auxiliary rod and the rear of said links having its upper end coupled to the lower end of the arc lever and the other link having its upper end in oper-

ative relation with the distributing valve stem, substantially as described.

51. In steam engine valve gear, the combination of a bridge on the engine frame, a rocking member supported by said bridge, means for rocking said rocking member, an upright, reciprocatory arc lever coupled between its ends to the outer end of said rocking member, means for guiding one end of said arc lever for approximately upright reciprocation, an auxiliary crank, an auxiliary rod coupled to said crank, and two approximately upright links each having its lower end coupled to the auxiliary rod and one having its upper end coupled to the oscillatory end of the arc lever and the other having its upper end in operative relation with the distributing valve stem, substantially as described.

52. In a steam engine valve gear, the combination of a bridge on the engine frame, a bearing seated on said bridge, a rocking member in said bearing, means for rocking said rocking member, an upright, reciprocatory arc lever coupled between its ends to the outer end of said rocking member, means for guiding one end of said arc lever for approximately upright reciprocation, an auxiliary crank, an auxiliary rod coupled to said crank, and two approximately upright links, each having its lower end coupled to the auxiliary rod and one having its upper end coupled to the oscillatory end of the arc lever and the other having its upper end in operative relation with the distributing valve stem, substantially as described.

53. In a steam engine valve gear, the combination of a bridge on the engine frame, a rocking member supported by said bridge and extending upward from its axis, means for rocking said rocking member, an upright, reciprocatory arc lever coupled between its ends to the upper end of said rocking member, means for guiding the upper end of said arc lever for approximately upright reciprocation, an auxiliary crank, an auxiliary rod coupled to said crank and two approximately upright links, each having its lower end coupled to the auxiliary rod and one having its upper end coupled to the lower end of the arc lever and the other having its upper end in operative relation with the distributing valve stem, substantially as described.

54. In a steam engine valve gear, the combination of a bridge on the engine frame, a bearing seated on said bridge, a rocking member seated in and extending upward from said bearing, means for rocking said rocking member, an upright, reciprocatory arc lever coupled between its ends to the upper end of rocking member, means for guiding the upper end of said arc lever for approximately upright reciprocation, an auxiliary crank, an auxiliary rod coupled to

said crank, and two approximately upright links, each having its lower end coupled to the auxiliary rod and one having its upper end coupled to the lower end of the arc lever and the other having its upper end in operative relation with the distributing valve stem, substantially as described.

In testimony whereof I have signed my

name, in presence of two witnesses, this 10th day of May, in the year one thousand nine hundred and thirteen.

WILLIAM SHERMAN BROWN.

Witnesses:

CYRUS KEHR,
H. P. STRAYER.
